UNITED STATES PATENT OFFICE.

JOHN F. O'BERT, OF LOS ANGELES, CALIFORNIA.

STARTING DEVICE FOR INTERNAL-COMBUSTION ENGINES.

1,077,292.

Specification of Letters Patent.

Patented Nov. 4, 1913.

Application filed October 8, 1912. Serial No. 724,610.

To all whom it may concern:

Be it known that I, JOHN F. O'BERT, a citizen of the United States, and residing at Los Angeles, in the county of Los Angeles 5 and State of California, have invented certain new and useful Improvements in Starting Devices for Internal-Combustion Engines, of which the following is a specification.

10 This invention relates to improvements in starting devices for internal combustion engines, and more especially for those employed upon auto and motor-cycles.

An object of the invention is to provide 15 a foot operated initial turning device for the engine shaft which in its operation will automatically make and break the connection with such shaft and will also relieve the operator from injury from accidental 20 back-firing of the engine.

A still further object is the provision of 25 a foot operating lever which in its operative movement automatically connects with mechanism capable of initially rotating the engine shaft and at the same time automatically through different elements brings such mechanism into operative engagement with the shaft and automatically releases upon a 30 premature explosion.

With these general objects in view and 35 others that will appear as the nature of the invention is better understood, the same consists in the novel combination and arrangement of parts hereinafter fully described, 40 illustrated in the accompanying drawings, and pointed out in the appended claims.

In the drawings forming a part of this 45 application and in which like numerals of reference designate corresponding parts throughout the several views: Figure 1 is a top plan view of the device showing its relation to the engine shaft but having the sprocket chain removed. Fig. 2 is a front side elevation of the foot lever and its adjacent operated mechanism. Fig. 3 is a central vertical transverse sectional view of 50 Fig. 2. Fig. 4 is a detail view of one of the peripheral dog and ratchets, and, Fig. 5 is a detail view of the pivotal end of the foot lever showing the return spring, the cover cap being removed therefrom.

Referring more in detail to the drawings, a stationary plate or portion 10 of the motor-cycle or machine is provided with a fixed stop axle 11 having its outer end reduced 55 forming a spindle 12. A foot lever 13 having a hub 14 is mounted for rotation upon the smooth surfaced portion of the spindle 12 and adjacent the annular shoulder 14' of the axle, said lever being normally held in 60 the position shown in Figs. 1 and 2 by the encircling hub spring 15 secured at one end to the spindle 12 and at the other end to the hub 14 while an adjustably positioned cover cap 16 is provided therefor, the lever being 65 retained upon said spindle by means of suitable devices, such as the lock nuts 17. Journaled upon the axle 11 and the inner portion of the hub 14 by means of the ball bearings 18 is the spool 19 having the central portion 70 20, connecting its opposite ends or disks 21 and 62. The studs 13' of the hub engage in the pockets 15' of the cap at the adjusted positions. Said spool disk 21 is provided with peripheral teeth 23 adapted to act as 75 a ratchet in connection with a plurality of dogs 22 pivoted upon the support 10 as best shown in Fig. 3. A pawl 24 being carried by the foot lever 13 normally engages the internal toothed rack 25 carried by the outer 80 spool disk 62. A clutch casing 26 having the hub 27 is mounted upon the spool hub 20 having the ball bearing 28 positioned therebetween while upon the exterior thereof of the annular flange 28 carried thereby is 85 rigidly mounted the sprocket wheel 29. Within the casing so formed and journaled upon the hub 27 is a further clutch member 30 to which the clutch or brake bands 31 are 90 operated by the levers 32 and links 33 are pivoted by means of the posts 34. Pivots connecting said levers 32 with the inner face of adjacent spokes 35 of the spool disk 62 are the links 36 having take-up springs 37. Said levers 32 are adjustably connected by the 95 spring mechanisms 38 upon both sides of the hub, it being noted that any movement of said levers 32 toward the hub and toward each other is adapted to result in a setting of the brake bands 31 into firm engagement 100 with the inner face of the flange 28 to thereby bring the power sprocket 29 in clutch

with the spool 19 through the wheel disk 62 thereof.

The outer free end 39 of the engine shaft is toothed for engaging the teeth upon a stub shaft 40 so positioned as to be brought into clutching engagement therewith upon relative longitudinal movement, said stub shaft having a small gear wheel 41 secured thereto. A sprocket chain (not shown) is adapted to transmit power between sprocket wheels 29 and 41 upon the forced rotation of the former. The lever arm 13 has a handle or pedal member 42 which under impulses of the foot forces the lever 13 in the direction shown by the arrow in Fig. 2 and with the pawl 24 engaging the teeth 25 of the wheel disk 62 of the spool 19 and whereby the spool is partially rotated upon an axle 11, the dogs 22 engaging the peripheral teeth of its disk 21 to prevent a rearward movement thereof. The spring mechanisms 38 are preferably of sufficient strength for setting the brake bands 31 against the inner face of the flange 28 whereupon the continued movement revolves the sprocket 29 and through the agency of the power sprocket chain (not shown) turns the small sprocket 41 and the stub shaft 40, which latter, when placed in clutch with the engine shaft 39 in the manner hereinafter set forth, imparts a starting movement to the said shaft.

The stationary support 10 is provided with a bracket 43 upon which is pivoted the angular rocker arm 44 having one end thereof engaging the relatively and rotatable collar 45 of the stub shaft 40. Also pivoted to the bracket 43 or an adjacent portion of the permanent support is the L-shaped lever 46 resiliently held in normal position against the adjustable stop 47 secured to said bracket by means of the coil spring 48. The lever arm 13 is normally positioned in engagement with the notch 49 of the short end 50 of said lever while pivoted upon said end and adjacent the termination thereof is the latch 51 having a limited length of movement. It will therefore be seen that upon moving the lever 13 for propelling the stub shaft 40 that the lever 46 is automatically moved upon its pivot and which through the agency of the spring 52 connecting said lever to one end of the rocker arm 44 thereby shifts the end 55 thereof which engages the collar 45 so that the stub shaft 40 is longitudinally moved into clutching engagement with the engine shaft 39.

The entire specific elements of the device have been described as well as the movement of the foot pedal 42 in accomplishing the rotation of the stub shaft 40 through the devised mechanism. From this and the description of the automatic means whereby

the stub shaft 40 is clutched with the engine shaft 39 the complete operation of the foot pedal and lever 13 in imparting the initial movement to the engine shaft 39 will be evident. The lever 46 being normally positioned by its pivotal spring 48 as shown in Fig. 1 insures the normal position of the foot lever and shaft clutch members in their unset or disengaged positions, which is also insured by the pivotal spring 15 of the lever 13. The revolutions of the spool 20 are always in one direction and are substantially one-fourth of a revolution upon each cranking operation.

A reverse movement or a kicking back of the engine shaft and the consequent reverse impulse given to the sprocket wheel 29 cannot turn the spool 19 as the same is held by the dogs 22 engaging the rear disk thereof and for this reason no reverse movement is imparted thereby to the lever 13 such as might injure the operator. The reverse movement however, of the sprocket 29 acting on the links 36, the outer ends of which are held stationary by the wheel disk 62 results in releasing the brake bands 31 of the clutch so that the sprocket 29 will be free to revolve.

While the forms of the invention herein shown and described are what are believed to be preferable embodiments thereof, it will nevertheless be understood that various changes and modifications may be made without departing from the spirit and scope of the invention as set forth in the appended claims.

What I claim is:—

1. A device of the class described comprising in combination with an engine shaft, a stationary axle, a spool journaled upon said axle, a stationary support, peripheral teeth upon the outer side disk of said spool, dogs pivoted to said support adapted for engagement with said teeth, an internal rack upon the inner side disk of said spool, a foot lever journaled upon said axle, a pawl pivoted to said lever adapted for normal engagement with said internal rack, a sprocket wheel journaled upon said spool between the side disks thereof, clutching means positioned between said sprocket wheel and said inner side disk of said spool, and operative connections between said sprocket wheel and engine shaft.

2. A device of the class described comprising in combination with an engine shaft, a stationary axle, a spool journaled upon said axle, a stationary support, peripheral teeth upon one side of said spool, dogs pivoted to said support adapted for engagement with said teeth, an internal rack upon the other side of said spool, a foot lever journaled upon said axle, a pawl pivoted to said lever adapted for normal engagement

with said internal rack, a clutch casing journaled upon said spool between the opposite sides thereof, a sprocket wheel mounted upon the exterior of said casing, a stub

5 shaft adapted for engagement with the engine shaft, a small sprocket wheel upon said stub shaft, operative connections between said sprocket wheels, and means including

brake bands within said casing adapted for clutching the latter to said spool. 10

In testimony whereof I affix my signature in presence of two witnesses.

JOHN F. O'BERT.
